CLAIM

The ornamental design for a pendant lamp as shown and described.

DESCRIPTION

FIG. 1 is a top perspective view of the pendant lamp; FIG. 2 is a front elevational view of the pendant lamp; FIG. 3 is a rear elevational view of the pendant lamp; FIG. 4 is a left side elevational view of the pendant lamp; FIG. 5 is a right side elevational view of the pendant lamp; FIG. 6 is a top plan view of the pendant lamp; and, FIG. 7 is a bottom plan view of the pendant lamp.

The broken line portions of the drawings are included to show portions of the pendant lamp that form no part of the claimed design.

The break lines shown in FIGS. 1-5 are not part of the claimed design and represent that no particular length is claimed.

1 Claim, 7 Drawing Sheets
